UNITED STATES PATENT OFFICE.

FREDERICK E. THEILACKER, OF MILWAUKEE, WISCONSIN, ASSIGNOR TO NORMAN P. HARSHBERGER, OF CHICAGO, ILLINOIS.

SHINGLE.

Application filed August 30, 1926. Serial No. 132,346.

This invention relates to composition shingles, and has for one of its objects providing shingles of such shape that they may be conveniently cut without waste from sheets of shingle material, and can be assembled upon the roof in such a manner as to present a novel and pleasing appearance. Another object is to provide improved means for locking down the lap or exposed portion of the shingles so as to eliminate the tendency of the edges thereof to turn upwardly under the stress of weather, the warping tendency of the sun, or otherwise. Another object is to fulfill the foregoing conditions and also to reduce the amount of lapping required in order to properly protect the roof.

Of the accompanying drawings Fig. 1 is a plan view of a sheet of shingle material showing how the shingles, which embody the features of my invention, are cut from the sheet without waste; Fig. 2 is a plan view of a number of shingles indicating their appearance when assembled on the roof; and Fig. 3 is a plan view of an individual shingle, somewhat enlarged.

The shingles 4 when assembled on the roof are normally placed in horizontal rows 5, though this is not essential to my invention. The shingles in the rows have their adjacent ends lapped and the rows themselves are lapped on the adjacent underlying rows. This lapping in either case may be as much as is desired, but the amount of lapping is determined by the particular shape of the shingle. In forming the shingles I provide adjacent the lower edge thereof slits or slots 6. This slit is in the exposed or lap portion of the shingle and the purpose of the slit is to lock the lap 8 of the shingle down. This is accomplished by means of a lug or lock 7 in an adjacent underlying shingle, the lug 7 passing upwardly through the slit 6, and then projecting downwardly and thus locking down the lap portion of the shingle. The amount of lapping of one row upon the other is determined by the positions of the slits 6 or the lugs 7. By having the lug 7 nearer the lower edge, or having the slit 6 farther from the lower edge, the lapping of the rows will be greater. Similarly with reference to the end lapping of the adjacent shingles in the rows. This will depend upon the length of the shingles and particularly the distance the end 9 projects beyond the slit 6. Hence the amount of

lapping can be reduced as much as is consistent with proper protection. 55

It will be noticed that the ends of the shingles are offset, the purpose being to position the lug 7 properly, and to make a single lug at one end of the shingle to take the place of two similar lugs, one-half the size of a single lug, one on each end of the shingle. This simplifies the shingles and the laying thereof. In order to conveniently cut the shingles without waste the edges of the two ends are made 60 broken as indicated and homologous. However, the exact form of these edges is not material to my invention. The corners 10 and 11 might be made oblique either obtuse or acute, and other modifications might be made in the 65 shape of the shingle by those skilled in the art without departing from the spirit of my invention as disclosed by the following claims. 70

In order to more completely cover the lapped ends of the shingle the projecting lap 75 8 is formed, this portion lapping over the ends of the underlying shingles in the adjacent lower row. And in order to cut the shingles without waste this lap is made substantially one-half as long as the main body of the 80 shingle, the lap 8 of one shingle being cut from the body of two adjacent shingles so as to form therein the recesses 12.

I claim as my invention:

1. A rectangularly shaped flat, composition shingle, a rectangularly shaped lap projecting from the central portion of one side edge, said lap having a slit in its central portion, and a lug fixed to the central portion of an end edge of said shingle, said lug being 85 adapted to enter into a slit of a similar shingle. 90

2. A shingle having the shape of a parallelogram and having an interior longitudinal slit in the central portion of one side adjacent the edge, and a lug fixed to the central portion of one end only, the lug being adapted to enter a similar slit in a similar shingle, said shingle having the lug edge and the opposite edge offset and homologous. 95

3. A plurality of shingles assembled in horizontal rows with the shingles in each row lapping with the adjacent shingles of the same row, and with the sides of one row lapping with the sides of the adjacent rows, 105 each of said shingles having a slit in its lower side and a lug fixed to one end, the respective lugs of one row being interlocked with

the slits of the adjacent overlapping row, and with the lapping ends of the adjacent shingles in the same row having broken but homologous edges.

5. 4. A shingle having the general shape of a parallelogram and having a lap projecting from one edge, said lap having an interior slit therein spaced from the outer edge of the lap, and said shingle having a lug fixed to an end of the shingle and projecting outwardly in the plane of the shingle beyond the end edge and adapted to enter a slit of another similar shingle when assembled on a roof.
10. 5. A plurality of shingles assembled on a roof in overlapping rows, each of the shingles having an inner slit in the central lower portion of its exposed lap, and a lug fixed to an edge of the shingle at the joint formed with the adjacent shingle in the same row and

overlapping the said adjacent shingle, the 20 central portion of said lug registering substantially with the said edge, and the lug interlocking with a slit of a shingle in the adjacent overlying row.

6. A shingle having the general shape of a parallelogram and having a lap projecting from one edge, said lap having an interior slit therein spaced from the outer edge of the lap, and said shingle having a lug fixed to an end of the shingle and projecting outwardly 25 beyond the end edge and adapted to enter a slit of another similar shingle when assembled on a roof, said lug also extending inwardly of said end edge a material distance.

In testimony whereof, I hereunto set my 30 hand.

FREDERICK E. THEILACKER.
